UNITED STATES PATENT OFFICE.

JOSEPH H. SMEDLEY, OF NARBERTH, PENNSYLVANIA.

PUSH-BUTTON SWITCH.

1,079,271.

Specification of Letters Patent.

Patented Nov. 18, 1913.

Application filed March 26, 1913. Serial No. 756,981.

To all whom it may concern:

Be it known that I, JOSEPH H. SMEDLEY, a citizen of the United States, residing at Narberth, in the county of Montgomery and State of Pennsylvania, have invented new and useful Improvements in Push-Button Switches, of which the following is a specification.

This invention relates to improvements in circuit closers and has particular application to push button switches for closing the circuits of electric bells and other analogous annunciators.

In carrying out the present invention, it is my purpose to provide a push button switch which will be in the nature of a combination circuit closer and electric lamp, the latter being slidable longitudinally to close the circuit controlled by the circuit closer and capable of illumination so that the bell or other annunciator circuit controlled by the circuit closer may be readily and conveniently closed at night.

It is also my purpose to provide a novel form of switch for making and breaking the lamp circuit so that the lamp may be energized and deenergized in accordance with prevailing conditions.

Furthermore, I aim to provide a push button switch embodying in its construction among other features a circuit closer controlling a bell or other annunciator circuit for a lamp adapted for sliding and rotary movement so that the circuit closer may be opened and closed and the lamp connected in and cut out of the circuit thereof respectively when necessary.

It is also my intention to provide a push button switch which may be illuminated when conditions warrant, as for instance, in the night time so that the push button may be readily and conveniently located and the annunciator circuit controlled thereby closed and which will embrace the desired features of simplicity, efficiency and durability coupled with cheapness of cost in manufacture and installation.

With the above and other objects in view, the invention consists in the construction, combination and arrangement of parts hereinafter set forth in and falling within the scope of the claims.

In the accompanying drawing; Figure 1 is a plan view of a push button switch constructed in accordance with my present invention. Fig. 2 is a longitudinal sectional

view thereof, the interior mechanism being shown in elevation. Fig. 3 is an enlarged fragmentary sectional view through the casing showing the mechanism in section. Fig. 4 is a cross sectional view on the line 4-4 of Fig. 3, and Fig. 5 is a fragmentary side elevation of one side wall of the casing.

Referring now to the accompanying drawing in detail, the numeral 1 designates a base plate constructed of any suitable material and formed with apertures through which screws or other fastening devices are adapted to be passed so that the base may be fastened upon a suitable or convenient object, while 2 designates a face plate having formed integral with the marginal edges thereof side and end walls provided with inturned flanges 3 adapted to contact with the front face of the plate 1, the plate 1 and flanges 3 being formed with alining openings to receive securing screws 4. Thus, it will be seen that the contiguous inner surfaces of the front plate 2 and side and end walls formed integral therewith and the plate 1 constitute a housing or casing. If desired, suitable indicia, such, for instance, as the number of a house in which the device is installed, may be inscribed upon the front face of the plate 2.

The front plate 2 of the casing, at an appropriate point, is formed with an opening 5, while suitably secured to the inner surface of the plate 2 adjacent to the wall of the opening 5 and surrounding such opening are brackets 6 suitably spaced apart and carrying an annulus 7 preferably composed of insulating material and disposed coaxial with the opening 5 in the plate 2. Mounted within the annulus 7 for longitudinal sliding and rotary movements therein is a relatively narrow ring 8 composed of some suitable material and carrying a relatively long threaded socket member 9 extending beyond the confines of the annulus and threadedly receiving a metallic plug 10 carrying an electric lamp bulb 11 disposed within the opening 5 and capable of sliding movement in such opening and rotary movement therein. Suitably fastened to the rear wall 105 of the casing or housing formed of the base plate 1 and preferably coaxial with the opening 5 in the front wall of such casing is a stationary contact 12 adapted to be engaged by a spring contact 13 having one terminal or end suitably fastened to the rear wall of the casing, while the op-

2. A device of the class described comprising a casing having an opening in the front wall thereof, an annulus disposed within the casing coaxial with the opening therein, a 5 ring disposed within said annulus and capable of sliding and rotary movement therein, a lamp carried by said ring and normally projecting out of the casing by way of the opening therein, a pair of contacts disposed 0 within the casing in the path of sliding movement of said lamp, an annunciator circuit including said contacts and adapted to be closed when said lamp is moved inwardly of the casing, a switch for closing the lamp 15 circuit when the lamp is rotated, and means for rotating said lamp whereby the switch will be closed.

3. A device of the class described comprising a casing having an opening in the front wall thereof and formed with a slot 20 in one side wall thereof, an annulus disposed within the casing coaxial with the opening therein and having a slot formed therein alining with the slot in the side wall 25 of said casing, a ring disposed within said annulus and capable of sliding and rotary movement therein, a lamp carried by said ring and normally projecting out of said casing by way of the opening therein, a pair 30 of contacts disposed within the casing in the path of sliding movement of the lamp, an annunciator circuit including said contacts and adapted to be closed when said lamp is moved inwardly of the casing, a switch for 35 closing the lamp circuit when the lamp is

rotated, and a manipulating handle for said switch connected to said ring and extending outwardly of the casing by way of the slots in the annulus and in the side wall of the casing.

40

4. A device of the class described comprising a casing having an opening in the front wall thereof, an annulus disposed within the casing coaxial with the opening therein, a ring disposed within said annulus 45 and capable of sliding and rotary movement therein, a lamp carried by said ring and normally projecting out of the casing by way of the opening therein, a pair of contacts disposed within the casing in the path of 50 sliding movement of said lamp, an annunciator circuit including said contacts and adapted to be closed when said lamp is moved inwardly of the casing, a switch for closing the lamp circuit when the lamp is 55 rotated and comprising a pair of contacts secured to the outer surface of said annulus at diametrically opposite points, and a pair of contacts secured to said lamp at diametrically opposite points and rotatable therewith to engage the first-mentioned contacts, and means for rotating said lamp whereby the switch will be closed.

In testimony whereof I affix my signature in presence of two witnesses.

JOSEPH H. SMEDLEY.
